ATTORNEY

UNITED STATES PATENT OFFICE

JOHN CAVANAGH, OF NORWALK, CONNECTICUT, ASSIGNOR TO HODSHON-BERG, INC., OF NORWALK, CONNECTICUT

STRAW HAT

Application filed May 24, 1930. Serial No. 455,263.

This invention relates to straw-braid hats of the type having an annular section of relatively flexible material or characteristics interposed between the brim of the hat and the base of the crown so that the hat will more readily and more comfortably conform to the head of the wearer than is the case with hats made entirely of rigid or stiffened straw-braid.

10 The object of this invention is to provide an improved hat of the character described having an annular flexible portion composed entirely of cloth strips stitched together and to the adjacent edges of the straw-braid of the 15 hat. A further object of this invention is to provide an improved hat structure in which a strip of cloth material is arranged with overlapping edges having toothed or zig-zagged edges to approximately match the 20 design of the straw-braid of the hat, these strips being stitched together and to the adjacent edges of the brim and of the crown of the hat. A still further object is to provide a hat comprising a stiffened straw-braid brim, 25 a stiffened straw-braid crown and a flexible cloth connecting part of annular form exposed to view at the upper and under sides of the brim.

With these and other objects in view, the 30 invention consists in the novel construction and arrangement hereinafter described illustrated in the accompanying drawings and particularly pointed out in the appended claim, it being understood that various 35 changes in the arrangement may be made without departing from the spirit of the invention or sacrificing any of the advantages thereof.

In the drawings, Fig. 1 is a perspective 40 view of a hat made in accordance with this invention; Fig. 2 is an enlarged detail view partly in section and partly in perspective showing the connection between the brim and the base of the crown. Fig. 3 is a view of the 45 underside of the brim of a hat showing how the cloth strip is applied thereto and Fig. 4 is a view showing a modified arrangement in which cloth in the form of annular or endless strips of varying sizes are assembled together.

Referring to Figs. 1, 2 and 3 of the drawings, the hat is made with a straw-braid brim 1 which may be of any suitable or well-known construction and may be stiffened in the usual way. The crown 2 of the hat is also of any 55 well known form and is suitably stiffened.

In the form shown in the drawings, a strip of felt or other cloth 3 is secured to the inner edge of the brim 1 on the upper surface thereof and this strip is wound in spiral form with 60 its edges overlapping each other and the spirally wound strip is assembled to form the base or lower part of the crown of the hat and is attached to the lower extremity of the straw-braid crown at 4. At the under surface 65 of the brim 1 a similar strip of cloth 5 is secured in place in the same way and is wound in the form of a spiral and connected to the strips 3 and/or to the lower edge of the straw-braid of the brim 2 of the hat. 70

The cloth portion forming the base of the crown of the hat is concealed at the outside of the hat by the usual ribbon band 6 and is concealed at the inside of the hat by the usual 75 leather sweat band 7.

The cloth strips forming part of the brim of the hat are exposed to view at the upper and under side of the brim and the exposed edges of the strip are cut in toothed or zig-zagged form to match, or approximately 80 match, the straw braid of the brim of the hat. The strips are preferably made of felted material but may be made of other suitable cloth of a sufficiently strong and flexible nature. Both edges of the strips are preferably cut 85 in the toothed or zigzag form as shown.

Fig. 4 shows a modified arrangement in which—instead of employing spirally wound strips—annular or endless strips 8 of felted material are employed, the outer and the inner edges of these annular strips being both cut in toothed or zigzag shape and these parts being made of varying sizes so that they may be assembled together to provide overlapping edges having substantially the appearance of 90 a straw-braid hat.

Although the drawings and above specification disclose the best modes in which I have contemplated embodying my invention, I desire to be in no way limited to the details of 100

such disclosure for in the further practical application of my invention many changes in form and construction may be made as circumstances require or experience suggests without departing from the spirit of the invention within the scope of the appended claim.

What I claim is:

10 A straw-braid hat of the character described, comprising a flat stiffened brim, a stiffened crown, and means for connecting said brim and crown, said means comprising an annular flexible portion extending horizontally through a portion of the brim and 15 vertically through a portion of the crown, and spacing apart said brim and crown, said portion consisting of overlapping strips of felted cloth having their edges exposed to view in the brim portion and concealed from view in 20 the crown portion only by the usual ribbon and sweat band.

In testimony whereof I have signed my name to this specification.

JOHN CAVANAGH.
